US0D1089183S

(12) **United States Design Patent** (10) **Patent No.:** **US D1,089,183 S**
(45) **Date of Patent:** **** Aug. 19, 2025**

(54) **DATA PROCESSING UNIT**

(71) Applicant: **SITA B.V.**, Rotterdam (NL)

(72) Inventors: **Johannes Theodorus Georgius Roelofsen**, Rotterdam (NL); **Mathieu Eduard Keizer**, Rotterdam (NL)

(73) Assignee: **SITA B.V.**, The Hague (NL)

(**) Term: **15 Years**

(21) Appl. No.: **29/868,712**

(22) Filed: **Dec. 12, 2022**

(30) **Foreign Application Priority Data**

Jun. 13, 2022 (EM) 009060056-0009

(51) **LOC (15) Cl.** **18-02**

(52) **U.S. Cl.** ..... **USPC** **D18/53**

(57) **CLAIM**

The ornamental design for a data processing unit as shown and described.

DESCRIPTION

FIG. 1 is a front top perspective view of a data processing unit.

FIG. 2 is a back top perspective view thereof.

FIG. 3 is a front view thereof.

FIG. 4 is a back view thereof.

FIG. 5 is a top view thereof.

FIG. 6 is a bottom view thereof.

FIG. 7 is a right view thereof; and,

FIG. 8 is a left view thereof.

The broken lines shown in the drawings illustrate portions of the data processing unit that form no part of the claimed design.

1 Claim, 8 Drawing Sheets
